COOLER AND CARBONATOR

John L. Barr, Baltimore, Md.

Application August 28, 1948, Serial No. 46,572

3 Claims. (Cl. 257—242)

1

This invention relates to the treatment of liquids to be cooled and/or carbonated, and particularly to coolers and carbonating processes and equipment. It has among its objects to provide a new and improved cooler and carbonator assembly that will avoid one or more of the disadvantages and limitations of the prior art.

Another object of this invention is to provide a new and improved cooler and carbonator that will be effective, efficient, compact and economical in construction.

A further object of the invention is to provide a new and improved cooler and carbonator that may be readily inspected, thoroughly cleaned and easily assembled, whenever it is desirable to do so.

Another object of the present invention is to provide a liquid cooler with diffusers and baffles for directing the flow of liquid in a semi-thin and irregular stream for fast cooling and directing the liquid to a spiral chute for conveying the liquid downwardly in a thin stream and charging it with carbon dioxide.

A further object of the present invention is to provide a liquid cooler having a center evaporator surrounded in spaced relation by a coiled suction line, with a diffuser positioned on and cooled by the evaporator and a baffle plate contacting the inner wall of the cooler and cooled by suction coils so the cold may be imparted to the liquid as it passes between the diffuser and baffle plate.

A further object of the present invention is to provide a cooler having a double walled evaporator centrally positioned in a spaced double walled container, with said spaces filled with oil to act as a conductor of cold to the liquid passing through the cooler and to act as a buffer against fast temperature droppage when the flow of the cooling medium has been stopped.

A further object of the present invention is to provide a combined cooler and carbonator having a center evaporator and surrounding suction coils for cooling a spiral conveyor and the liquid which passes in a thin stream along and through it from an inlet and during its passage subjecting the liquid to carbon dioxide gas to carbonate the liquid and passing it from the cooler and carbonator.

Other objects will become apparent as the invention is more fully set forth.

To make this invention clear, reference is made to the appended drawings, in which a particular form of the invention is indicated. These draw-

2

ings together with the following description outline the particular form by way of example, illustrate its principles and portray its objects. At the same time, the claims emphasize the scope of the invention.

Referring to the drawings:

Figure 1 is a sectional view in plan of a cooler used in this embodiment of the invention, looking along line 1—1 of Figure 2;

10 Figure 2 is a partial sectional view taken along the line 2—2 in a longitudinal direction, of Figure 1;

Figure 3 is an underneath view looking upwards of a carbonator used in this invention and indicated in Figure 4;

15 Figure 4 is a longitudinal section through a carbonator used in this embodiment with piping connections coupled thereto;

Figure 5 is a sectional view in a plan along line 5—5 of Figure 4;

20 Figure 6 is a sectional view in plan along line 6—6 of Figure 4;

Figure 7 is a diagrammatic view of the cooler and carbonator assembly coupled together;

25 Figure 8 is a perspective view of a sinuous diffuser used in the cooler and mounted on its central or evaporator shell;

Figure 9 is a perspective view of a baffle plate used in the cooler in conjunction with the diffuser.

30 Similar reference characters refer to similar parts throughout the drawings.

In the structure shown in Figs. 1 and 2, a cooler consists of a cylindrical casing 10, which has a removable bell-shaped cover 11 slipped within its upper edge portion 12. The cover has insulation 13 imbedded in it and held in place by an under plate 14. The plate 14 is securely fastened to the cover wall 21 by welding, riveting or other conventional method and leaves a space 15 under but within the cover, as indicated. The edge of the cover wall 21 rests on a top disc-like plate 16 that has a dome 17 formed at its central area leaving a peripheral flat ring area about it on which the wall 21 rests at its periphery. A ring plate 18 rests on the upper edge of the casing and is held thereon by the plate 16 and closes in an annular peripheral portion thereof. This portion includes a compartment 19 with insulation 13 therein and an annular oil chamber 20 next to it. The insulation forms a lining about the wall 24 forming part of oil chamber 20 on one side and the outside wall 22 of the casing 10 on the other. The insulation is preferably of 40 substantially rigid material and insulates the

oil chamber 20. The oil 23 is prevented from overflowing out of the chamber 20 by the plate 18, which closes it. The chamber 20 leads to the bottom portion of the casing into a shallow cylindrical chamber 25, which covers the entire transverse area within the casing at the bottom, except as limited by the insulation 13 intervening between the bottom 26 of the chamber 25 and the bottom wall 27 of the casing. This chamber 25 has another oil chamber 26 extending vertically up from it at the middle of the cooler. This chamber 26 surrounds refrigerant shell 28 which takes up an axial position in the cooler, and also contains the oil 23. The outer portion of the chamber 26 is formed by an inverted cylinder 29 having walls 37. The oil 23 is of a heat conducting nature, and low specific gravity.

A band 30 of metal or other suitable material is welded or fastened on the exterior surface 22 of the casing 10 at its upper portion 12 so as to form a socket for the cover 11 to insert and fit into. The oil chamber 20 is of circular or cylindrical form and contains a tubular coil 31 of a suitable number of turns, extending for the greater part of its length. A screw-threaded boss 32 is formed at each end of the coil for the insertion and threading of nipples 33 and 72 therein, and serving as inlet and outlet for the circulation of the refrigerant medium 35 therethrough and not interfering with the removal of the coil. The interior of the shell 28 is fed with the same medium 35 through the primary inlet and outlet piping, 33 and 34 respectively. The refrigerant 35 escaping from the inlet pipe 33 into the evaporator shell 28 serves to cool through its walls the column of oil 23 surrounding it, thence through the walls 37 of the cylinder 29 where the coldness is transferred through the diffuser to the liquid beverage 36. The beverage 36 is fed into the chamber 38 through the inlet piping 39 which is provided with perforations 40 to spread the beverages 36 throughout the chamber 38 so it will be cooled quicker by the cooled walls of the diffuser 42 which are cooled by the walls 37 of the cylinder 29 which are cooled by the oil 23 from the walls of the shell 28, and the baffles 43 which receive their lowered temperature from the inside shell 44. The shell 44 separates the beverage 36 from the cooled oil 23 and is provided with a bottom plate 45 which is usually welded to the walls 37 of the cylinder 29. The bottom plate 45 is provided with feet 46 to rest against the bottom 26 connected to the wall 24 and maintain the cylindrical chamber 25 so the oil can flow through and be drained through the nipple 47 and valve 48 when necessary. The cooler is supported by legs 54. A spacer ring 55 surrounds the inlet piping where it enters the casing and prevents it from coming into contact with the low temperature oil 23 in the cylindrical chamber 25 and become frozen at that point, the atmospheric air insures a certain amount of insulation at that point. The refrigerant 35 is fed from a line 56 to a float valve 57 mounted on a bracket 64. The float valve 57 maintains a flooded liquid level at all times. After leaving the float valve the refrigerant passes through a line 58 to a manually operated valve 59 to a T 60 having a refrigerant charging connection 61 at one side and a nipple 62 connected to a magnetic valve 53 at the other, then passing along a pipe 65 to a T 66 which is connected at one side by a nipple 67 to an L 68 through a nipple 69 to a manually operated valve 70 which controls the passage of the refrigerant through inlet 33 thence

into the evaporator shell 28 where it rises and is drawn down through a refrigerant suction or outlet pipe 34, thence through an L 89, nipple 90 into one end of a T 73 a nipple 72 screwed into one end of the T 73 attaches it to the lower boss 32 of the spiral suction coils 31, which carry the refrigerant suction through the coils 31 which are immersed in the oil 23 and helps to cool the baffles 42 and impart some of its low temperature to the liquid passing through the beverage chamber 38. The refrigerant passes up through the coil boss 32 and nipple 74 and passes through a back pressure valve 75 and line 76 to the heat exchanger to the compressor. The bottom of the T 73 is equipped with a nipple 77 which allows a booster charge of refrigerant to be fed directly into the suction coils 31 after it passes through T 66, nipple 78, magnetic valve 63, nipple 79, manually operated valve 80, nipple 81, pipe union 82, nipple 83, T 84, nipple 85, L 86, nipple 87, manually operated valve 88 to the nipple 77 as described above.

The diffuser element 42 is of hollow star like contour cross-sectionally, and made of flat metal with its longitudinal edge portions 48 aligned with one another without being fastened. This allows for a certain amount of resiliency when the element is slid down over the peripheral wall of the shell 28 and makes sufficient contact therewith to act as conducting vanes thereon. The element extends its star legs 49 outwardly from the center and serves as a partial barrier in the chamber 38. The baffle member 43 is formed in reverse to the element 42 with its inwardly appened formations 50 extended into the valleys 51 between the legs 49 sufficiently to provide a sinuous path for beverage 36 to circulate in. The baffle member 43 is inserted in the chamber 38 and expanded to resiliently engage against the peripheral shell 44 of the chamber 38. It is made of flat metal preferably with its edge portions 52 aligned and bent into cup form to over lap the edge portions 48 of the diffuser element 42, as illustrated in Figure 1. The outlet pipe 53 is placed on the other side of the baffle formed by the edge portions 48 and 52. This produces a flow in the beverage through the sinuous path provided by the baffle member 43 and the diffuser element 42. The service connections and piping to and from the cooler are also provided and their arrangement is described in a later portion of the specifications.

In Figure 4 and its cooperating figures, the construction of a carbonator 127 is shown. Its structure is very similar to that of the cooler, having a casing 91, a cover 92, with insulation 13 in the compartment 93 surrounding the annular oil chamber 94. This chamber 94 connects at the bottom of the casing through a shallow cylindrical chamber 95 to the central refrigerant chamber 96 around the evaporator shell 97. Between the oil and refrigerant chambers 94 and 96 and encompassed by same is the beverage chamber 98 annularly positioned therein. This chamber has its top wall 99 perforated by perforations 100 and opening in a space 101 above that is enclosed over by a dome plate 102 similar to that dome 17 in the cooler casing 10. The chamber 98 is fed with the beverage 36 from the cooler through the inlet pipe 103 and covers the top wall 99 until it reaches the perforations in the latter and drops throughout into the beverage chamber 98. The drops of beverage fall on the tilted surface of a helical plate 104 and is provided with holes 145 and mounted on the inverted sleeve 105 which forms the outer portion

of the chamber 96 which covers the peripheral wall of the evaporator shell 97 and form a curtain along its edges which are spaced from the outer wall 106 of this chamber. In dripping down, this curtain of beverage 36 contacts the carbonated gas flowing in through the pipe 107 and both are intimately mixed together. The carbonated mixture is then drawn off through the outlet pipe 108. The chamber 94 has a helical tubular coil 109 immersed in the oil 23 and served by the inlet and outlet piping 110 and 111 respectively. The refrigerant passes through the float valve 57 and other piping and valves already described for the cooler and passes through the inlet 33 into the evaporator shell 97 which is similar to the evaporator shell 28 described. If ammonia is used as the refrigerant it is drawn through the outlet 34 as already described. If Freon is used as the refrigerant a bleeder pipe 112 with a hole 113 in it is used. The hole is used for drainage. The tube 112 is connected to the inlet 110, fittings 114, valve 115 and fittings 116, 117 and 118.

The coil 109 is supported in the casing in a suitable manner, and may be removed bodily whenever necessary or desirable to do so. Similarly with the helical plate 104.

The operation of the assembly is provided for as follows. The coolant from a conventional refrigerant system 119 is passed through piping 56 to the float valves, coils and shells of both the cooler and carbonator. The coils cool the oil 23 in the chambers which in turn cools the walls of the beverage chambers and does the work in a very steady and effective manner. The beverage 36 is then sent from an extraneous source through the piping 39 to the cooler casing 10 where it is cooled in the chamber 38 by the action of the coolant circulating in the coil and evaporation in the shell. Then after a suitable period, required for the beverage to circulate in the chamber 38 and against the diffuser plate 42 and baffle member 43, the beverage is passed through the piping 53 to the carbonator. The beverage flows through the inlet piping 103 and enters into the beverage chamber 98 through the perforations 100 in its head and passes in a curtain over the helical plate 104 mixing with the carbon dioxide gas entering through the inlet piping 107 connected to a suitable carbonic gas cylinder 120. For cooling and carbonating, an electric water level probe operates a liquid inlet control valve for maintaining a liquid level in the bottom of the cooler. From the carbonator casing the mixed beverage is piped through the piping 121 to a suitable dispensing machine. The float valve units are set to work at suitable levels of the beverage in the cooler and carbonator respectively. The magnetic valves close off the flow of liquid refrigerant when the refrigerating mechanism automatically shuts down.

The conventional control of the piping serves to provide any particular or desirable method of controlling the mediums used in the assembly, and do not need any particular extension of the description in their regard.

There are a number of distinct features of the assembly. The arrangement of the covers permits ready access to the interior of the casing. The coils may be removed, and the baffle member diffuser elements and helical tray disconnected, for cleaning or other reasons. The purpose of the oil in the assembly is to provide for a better heat exchange, to provide for a pressure reinforcement to the wall of the bever-

age chamber and lessen their possibility of bursting under beverage pressure and to surround the coils and refrigerant chambers with a liquid tending to keep the walls clean and free from erosion. The oil can be of the light mineral type; a Prestone and water solution or special chemical liquids that will meet any general or special conditions of heat transfer. The cover is insulated. The beverage is cooled from areas inside and outside its retaining walls.

While one form of the invention is shown in the drawings and described in the specifications, it is not desired to limit this application for patent to this particular form, as it is appreciated that other forms could be made that would use the same principles and come within the scope of the appended claims.

Having thus described the invention, what is claimed is:

- 20 1. A heat exchanger for beverages comprising an outer casing, insulating means within said casing, a cylinder within said casing having a central perforation in its bottom plate and an upper open end, a coiled pipe within said cylinder adapted to receive a cooling medium, a shell within said cylinder spaced inwardly of said pipe, a second shell spaced from said first mentioned shell, a series of perforated baffles between said shells, means for supplying a carbonating gas at the bottom of said baffles, an inner cylinder within said casing extending within said aforementioned central perforation, and means for supplying a beverage to said inner cylinder and to the space between said shells and for withdrawing it therefrom.
- 25 2. A heat exchanger for beverages comprising an outer casing, a cylinder within said casing and spaced therefrom, insulating means between said cylinder and casing, a centrally perforated bottom plate for said casing, said casing having an open upper end, a shell within said cylinder and spaced therefrom, a coiled pipe in the space between the cylinder and shell for receiving a cooling medium, a second shell in said casing inwardly spaced from the first shell, said second shell being of general star shape and the walls of said first shell having convolutions following and spaced from the star shaped walls of the second shell, an inner cylinder in the casing spaced inwardly of the second mentioned shell and extending within the perforation in the aforesaid bottom plate, means for supplying a cooling medium to the coiled pipe and inner cylinder and for withdrawing it therefrom, and means for supplying a beverage to the space between the shells and for withdrawing it therefrom.
- 30 3. A heat exchanger for beverages comprising an outer casing, a cylinder within said casing and spaced therefrom, insulating means between said cylinder and casing, a centrally perforated bottom plate for said casing, said casing having an open upper end, a shell within said cylinder and spaced therefrom, a coiled pipe in the space between the cylinder and shell for receiving a cooling medium, a second shell in said casing inwardly spaced from the first shell, baffle means between said shells, an inner cylinder in the casing spaced inwardly of the second mentioned shell and extending within the perforation in the aforesaid bottom plate, means for supplying a cooling medium to the coiled pipe and inner cylinder and for withdrawing it
